UNITED STATES PATENT OFFICE.

CHARLES LORBER, OF BROOKLYN, NEW YORK.

FLEXIBLE KEY CASE.

Application filed October 28, 1925. Serial No. 65,275.

The main object of this invention is to provide a key case suitable for the storing of keys, having for one of its main objects to provide a simple and inexpensive article 5 provided with key suspension means pivoted in a support in such a manner that the keys will lie flat upon the body of the key case to reduce the bulk of the same that it may be conveniently carried in the pocket.

10 Another object is to provide a key case having a suspension hook or ring so constructed as to prevent the key from becoming inadvertently disengaged from the ring.

Still another object is to provide a key 15 case constructed in such manner that the same is entirely flexible thruout its width, so that it may readily bend to conform to its comfortable storage in the pocket.

The above and other objects will become 20 apparent in the description below, in which characters of reference refer to like-named parts in the drawing.

Referring briefly to the drawing, Figure 1 is a perspective view of the key case in 25 partly opened position.

Figure 2 is a partly sectioned front elevational view of the preferred type of key retainer unit.

Figure 3 is a side elevational view of Figure 2.

Figure 4 is a sectional elevational view thru a portion of the key case, showing the means of attaching the key retainer units 30 flexibly to the body of the key case.

Figures 5 and 6 illustrate modified forms of key suspension rings.

Referring in detail to the drawing, the numeral 10 indicates the back of the key case on which the key retainer units are 40 mounted. The back of the key case has a pair of side flaps 11 and 12 extending from opposing sides of the back. The back and the side flaps are formed of an integral piece of flexible material having semi-rigid characteristics, such as leather, or the like. At 45 the upper end of the back 10, a plate 13 of some semi-rigid composition, such as leather, is mounted by being stitched thereto, as illustrated at 14. Slits 15 are provided in the strip of leather 14 and these slits are spaced-apart and extend a distance of approximately half the width of the strip. The material between these slits 15 is 50 formed into outwardly projecting loops 16, the loops being adapted to receive eyelets 17 of support elements from which the key re-

tainer rings are suspended. The rings 17 are first slipped over the loops 16 and then the bottom edge of the strip 14 is secured to the back 10. After these loops 16 are formed, the bottom edge of the strip 14 is secured to the body 10 of the key case by a row of stitching 18. The eyelets 17 of the key support elements each consists of a pair of rings 18 and 19 which are secured integrally together face to face. Each of these rings has an ear 20 extending from one position. The ears are bent at right angles in opposite directions to one another, as illustrated in Figure 3, and have a hemi-spherical housing 21 attached thereto in which the heads 22 of the key suspension rings are rotatably fixed. These key suspension rings are formed essentially of a unitary piece of wire circular in cross section, and have an annular head, such as 22, formed at one end. From the head, the main stem 23 is suspended downwardly and at the lower end of the stem, a semi-circular curve or bend 24 is formed. This bend 24 forms the lower portion of an elliptical loop 25 which is smaller at the top than at the bottom and the end 26 opposite to the head 22 is curled helically to lie adjacent the stem 23 and in contact therewith. The end 26 courses downwardly and immediately below it, a ridge 27 is formed by bending the stem 23 below the end 26 into the loop 25, providing a hump so that a key such as 28, when in the loop 25, will be deflected away from the end 26 in order to 55 prevent the key from becoming disengaged or removed inadvertently out of the loop. In Figures 5 and 6, modified type of suspension rings are shown. Figure 5 illustrates a suspension ring having a head 28 formed similar to the head 22 of the preferred form of suspension ring. A stem 29 extends downwardly from the head 28, and at a position intermediate its length, is formed into a partial curve, providing an off-set extension 30, having a return bend 31 at its lower end, and then extending upwardly as an additional extension 32, which latter extends parallel to member 30 and has a semi-circular or half bend at its upper end so that the extreme end 33 of the extension 32 courses downwardly to form a loop 34. The suspension ring, illustrated in Figure 6, also has a head 35 and a straight stem 36 with a loop 37 formed by providing a large return bend 38 at its lower end and a smaller return bend 39 at its upper end, which smaller bend 60 65 70 75 80 85 90 95 100 105 110

is formed at the extreme end of an extension 40, thus providing an elliptical loop similar in all respects to the suspension ring illustrated in Figure 2 with the exception of the 5 ridge 27.

The key case illustrated herein has various advantages over some of the types now existing. In the majority of key cases, a rigid plate is used from which the key retainer support units, are suspended. Owing to the construction of the key retainer support units, a rigid plate has been necessary to further the purposes of these inventions. I propose to provide a strip of yieldable 10 material which ordinarily lies flat and may be bent to conform to the shape of the pocket or the body when the key case is inserted in the pocket. This is taken care of by providing the flexible strip 14. Each 15 of the units from which individual keys are suspended is separate and distinct from one another. Such separation is made possible by providing the strip 14 with loops 16 in which the eyelet 17, forming the anchoring 20 means for the support elements of the keys, is movably secured. The hemi-spherical 25 housings 21 forming part of the eyelets 17 are slotted at some position and spread apart to permit the stems 23 of the key suspension 30 rings to be inserted. After the heads 22, 28, or 35, according to the type of suspension ring being used, is inserted into the housing 21, the latter is bent to close the slotted portion in order to retain the head 35 of the suspension ring permanently in place in the housing. The eyelet 17, housing 21, and a suspension ring of any of the types desired, form a complete unit upon which a 40 key may be suspended and are individually manipulated so that neither of the other units in the key case is disturbed. These units may be individually swung a distance of 180 degrees from the suspended position shown in Figure 1, to an upright position 45 180 degrees above the suspended position. The suspension rings are long enough to permit one of the units when swung to the vertical position 180 degrees from the suspended position, to project out of the end 50 edge of the key case so that the key attached to this particular ring may be used to advantage while the other keys are securely housed between the back 10 and closed flaps 11 and 12 of the key case.

55 Keys are inserted into the loops 25, 34, or 37, of the suspension rings by slipping the opening at the head of a key over the ends 60 26 by spreading these ends away from and out of contact with the stem 23 to which the ends lie adjacent. The keys are readily attached to the suspension rings in this manner, but sometimes the keys are inadvertently detached from the rings, which is caused by the key case lying in a peculiar position in the pocket so that in some unfor-

seen manner, the edge of the key head spreads the end 26 of the loop apart from the stem 23 to cause disengagement. To eliminate this detaching, the stem 23 of the preferred type of suspension ring is formed 70 into a ridge 27, which extends inwardly into the loop 25 directly beneath the extreme end 26 of the ring. If a key were to be moved upwardly in the loop 25 alongside the stem 23, said key would ride upon the ridge or 75 hump 27 and would be deflected away from the end 26, thus preventing the key at any time from coming into engagement with the end 26 of the loop 25.

I claim:—

1. A key case comprising a flexible back having flexible side flaps integral therewith, a flexible strip extending widthwise near one end of the back and stitched to and rigid with said back, said strip being slitted half way across its width, loops formed between said slitted portions, eyelets secured in said loops, a hemi-spherical housing secured to said eyelets, and elliptical rings suspended from said housing. 80

2. A key case comprising a flexible back having flexible side flaps integral therewith, a flexible strip extending widthwise near one end of the back, said strip being slitted half way across its width, loops formed between said slitted portions, key retainer units comprising a pair of rings secured face to face, ears extending oppositely from said rings, housings secured to said ears, and longitudinal elliptical looped additional 90 rings rotatably suspended from said housings. 95

3. A key case comprising a flexible back having flexible side flaps integral therewith, a flexible strip extending widthwise near one end of the back, said strip being slitted half way across its width, loops formed between said slitted portions, key retainer units comprising a pair of rings secured face to face, ears extending oppositely from said rings, housings secured to said ears, additional rings suspended from said housings comprising a stem, a head on said stem, said head being rotatably mounted within the housing and an elliptical loop formed at the lower end of said stem, the end of said loop being coiled helically to lie in contact with the stem adjacent thereto, and means for guiding a key away from the end of the loop. 105 110 115

4. A key case comprising a flexible back having flexible side flaps integral therewith, a flexible strip extending widthwise near one end of the back, said strip being slitted half way across its width, loops formed between said slitted portions, key retainer units comprising a pair of rings secured face to face, ears extending oppositely from said rings, housings secured to said ears, additional rings suspended from said housings 120 125 130

comprising a stem, a head on said stem, said head being rotatably mounted within the housing and an elliptical loop formed at the lower end of said stem, the end of said 5 loop being coiled helically to lie in contact with the stem adjacent thereto, means for guiding a key away from the end of the loop comprising a ridge formed by bending the stem beneath the end of the loop, said ridge providing a hump extending into the 10 loop, and the hump being adapted to deflect the course of a key in being moved upwardly away from the end of the loop.

In testimony whereof I affix my signature.

CHARLES LORBER.
